ATTORNEY

UNITED STATES PATENT OFFICE

2,132,117

TROUSERS

Samuel R. Korolick, Bath, Maine

Application April 21, 1937, Serial No. 138,126

1 Claim. (Cl. 2-228)

This invention relates to new and useful improvements in trousers.

The invention contemplates the provision of a pair of trousers in the form of ski pants, snow suit pants, or any other type of pants, particularly adapted for use by a child, although this invention may also be applied to trousers worn by an adult.

Still further the invention proposes the use of 10 fastener elements which extend the entire length of the side seam of a pair of trousers and which may be lowered to a position in which these side seams will be entirely open to permit the trousers to be easily engaged or removed from one's body.

15 As another object of the invention it is proposed to have the fastener elements so positioned that by lowering them to a position just below the hips the front or back portion of the trousers may be lowered.

20 Still further the invention provides for a Lastex or knitted material cuff to be applied to the bottom of the leg portions of the trousers and which are adapted to be opened and closed by the same slide fasteners which close the sections of the trouser proper.

25 Still further the invention proposes to so construct the trousers for use in connection with a non-separating or separating slide fastener, depending upon the use to which the garment is to be put. If a non-separating slide fastener is used a cloth strip is added to the bottom of the Lastex or knitted cuff for the purpose of permitting the slide fastener to extend entirely through the Lastex or knitted cuff to permit the trousers 30 to be easily slipped over one's shoes.

As a still further object of the invention it is proposed to provide independent fastening elements between the top edge of the trousers and a separate belt which is adapted to engage around 35 one's body for the purpose of permitting one section to be lowered while the other section is being supported upon the belt.

For further comprehension of the invention, and of the objects and advantages thereof, reference will be had to the following description and accompanying drawing, and to the appended claim in which the various novel features of the invention are more particularly set forth.

In the accompanying drawing forming a material part of this disclosure:—

Fig. 1 is a perspective view of a pair of trousers constructed according to this invention.

Fig. 2 is a fragmentary detailed view of a portion of Fig. 1 showing a modified form of the invention.

Fig. 3 is a view similar to Fig. 2 but showing a still further modified form of the invention.

Fig. 4 is a view similar to Fig. 1 showing a still further embodiment of the invention.

Fig. 5 is a perspective view of the belt per se 5 which is to be used in connection with the trousers shown in Fig. 4.

Fig. 6 is an enlarged sectional view taken on the line 6—6 of Fig. 4.

The removable trouser, according to this invention, comprises material in the form of a pair of trousers 10 having a body portion 10^a with front and rear sections 10^b, a crotch portion 10^c and leg portions 10^d. The sides of the trousers 10 are opened from the top of the body portion 10^a to the bottom of the leg portions 10^d and are formed with slide fasteners 11 for releasably closing these open sides. A Lastex or knitted cuff 12 is formed on the lower end of the leg portions 10^d and has the side opening extending 20 therethrough.

The slide fastener 11 is of the non-separating type and passes through the cuff 12 and terminates in a cloth binding 13 which is applied to the bottom portions of the cuff 12. The purpose 25 of adding this binding 13 which is of cloth or other non-stretchable material is to permit the cuff portions 12 to be separated in the open condition of the side openings to permit these cuff portions to be easily slid over one's shoes. 30

A half belt 14 is removably secured at its ends by a button and button hole construction 14^a upon the top corners of one of the sections 10^b so that this section may be retained raised while the other section 10^b is lowered. The latter section 35 10^b is also provided with buttons 14^a to receive the half belt 14 when removed from the other section 10^b, and then the belt in its new position, supports the connected section 10^b, while the other section 10^b may be lowered. 40

In Fig. 1 the half belt 14 is shown applied to the front section 10^b permitting the rear section 10^b to be easily lowered. The half belt 14 may be applied to the rear section 10^b permitting the front section 10^b to be lowered. 45

The operation of this form of the invention is as follows:—

The control slide of the slide fastener 11 is moved to its lowered position and one's feet are passed through the leg portions 10^d, the cuff 50 portions 12 and the binding material 13 and the front section 10^b of the body portion 10^a is drawn over the front portion of one's body and the half belt 14 is positioned around one's body to fixedly hold the front section 10^b in position. The slides 55

of the fasteners 11 are then raised to their top-most position to draw the rear section 10^b into position with relation to the front section 10^b and the half belt 14. When it is desired to drop 5 the back of these sections it is merely necessary to move the slide fastener to a position in which it is immediately below the hips of one's body permitting the section to move to the lowered position shown in Fig. 1. The half belt 10 14 may be switched to the rear section 10^b, as previously explained, and then the front section 10^b may be dropped.

In the modification shown in Fig. 2 the "Zipper" 11' is of the separating type and terminates 15 at the end portion of the Lastex cuff 12 making it unnecessary to apply the binding material to the bottom of the cuffs 12 as shown in Fig. 1. In other respects this form of the invention is similar to the one shown in Fig. 1 20 and corresponding parts may be identified by corresponding reference numerals.

In the modification shown in Fig. 3 the "Zipper" 11" is of the separating type and terminates 25 at the bottom of the leg portions 10^d of the trousers 10. A cloth cuff 12' is applied to the bottom of the leg portions 10^d and has one of its ends 12^a provided with a buckle 15. The other end 12^b of the cloth cuff 12' is reduced in width so as to permit it to be engaged with the buckle 15 to close the cuff 12' when the "Zipper" 11" closes the side opening in the trousers 10. In other respects this form of the invention is similar to the preceding ones, and 30 similar parts may be identified by the corresponding reference numerals.

In the form of the invention illustrated in Figs. 4-6, the construction is the same as that shown in Fig. 1 except for the fact that a belt 20 is provided at one of its ends 20^a with a buckle 21. 40 The other of its ends 20^b is provided with openings 22 which may be selectively engaged with the pin portion 21^a of the buckle 21 for positioning this belt on the waist portion of one's body. The outside face of this belt 20 is provided with 45 a number of snap fastener elements 23 which may be engaged with complementary snap fas-

tener elements 24 mounted on the inside face of the top portion of the front and rear sections 10^b of the trousers 10 to hold one of the sections in position upon one's body while the other section is in its lowered position.

The operation of this form of the device is the same as that shown in Fig. 1 excepting that when it is desired to lower either of the sections 10^b it is necessary to move the slide fastener 11 to a position immediately below the hips, 10 and then disengaging the snap fastener 24 from the complementary snap fasteners 23 upon the belt 20 and lowering either of these sections to the position illustrated by the dot and dash lines 15 10' in Fig. 4.

While I have illustrated and described the preferred embodiments of my invention, it is to be understood that I do not limit myself to the precise constructions herein disclosed and the right is reserved to all changes and modifications coming within the scope of the invention as defined in the appended claim.

Having thus described my invention, what I claim as new and desire to secure by United States Letters Patent is:—

An easily removable trouser comprising material in the form of a pair of trousers having a body portion with a front and rear section, a crotch portion and leg portions, the sides of said pair of trousers being opened from the top of 30 the body portion to the bottom of the leg portions, and fasteners for releasably closing these open sides, a belt for partially engaging around one's body cooperative fastening elements upon the ends of said belt and the top corners of said 35 sections for connecting the ends of said belt with one of said sections, whereby one section is free to be lowered when said fasteners at the sides of said sections are opened, said belt having its ends releasably attached to the corners 40 of said sections and transferable from one section to the other permitting the belt to be opened when it is desired to remove the garment from one's body, and also serving to support one section while the other is lowered.

SAMUEL R. KOROLICK.
